SHOT PATTERN CONTROL MUZZLE ATTACHMENT FOR FIREARMS

Edward Baden Powell, Pasadena, Calif., assignor
of one-half to Frank A. Pachmayr, Los Angeles,
Calif.

Application October 18, 1948, Serial No. 149,167

Term of patent 14 years

(Cl. D30—1)

To all whom it may concern:

Be it known that I, Edward Baden Powell, a citizen of the United States, residing at Pasadena, California, in the county of Los Angeles and State of California, have invented a new, original, and ornamental Design for Shot Pattern Control Muzzle Attachment for Firearms, of which the following is a specification, reference being had to the accompanying drawing, forming a part hereof, and in which:

Fig. 1 is a plan view of a shot pattern control muzzle attachment for firearms embodying my new design; and

Fig. 2 is a side view of Fig. 1.

I claim:

The ornamental design for a shot pattern control muzzle attachment for firearms, substantially as shown.

EDWARD BADEN POWELL.
